REFRIGERATING APPARATUS

Filed April 30, 1929

UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed April 30, 1929. Serial No. 359,395.

This invention relates to refrigerating apparatus and especially to beverage cooling and dispensing apparatus having a container discharging a beverage into the usual cooling chamber.

An object of the invention is to maintain the container having the supply of the drink to be dispensed in a cool state as well as the beverage chamber.

10 A further object is to produce a visible frost about the container in order that the coldness of the beverage may be appreciated. More specifically, the invention contemplates placing a frost producing means about the 15 bottle or other container so that the customer may readily see that the beverage withdrawn from the dispensing apparatus is cold.

Further objects and advantages of the present invention will be apparent from the following description, reference being had to the accompanying drawing, wherein a preferred form of the present invention is clearly shown.

20 In the drawing:
25 Fig. 1 is a view partly in elevation and partly in cross section disclosing beverage cooling and dispensing apparatus embodying the invention.

30 Fig. 2 is a similar view of a modification of the apparatus of Fig. 1.

One of the popular types of beverage cooling and dispensing apparatuses has been the type having an insulated beverage chamber with a supply container generally in the form 35 of an inverted bottle or demijohn, the major portion of which has been exposed to the warm air of the store or other locality. Accordingly, this invention contemplates the provision of cooling means about the container and especially such cooling means as 40 will produce a frost about this container. In this manner the beverage is pre-cooled before it descends into the storage chamber and especially has the advantage, from a sales 45 point of view, of calling the customer's attention to the cold state of the beverage by means of the covering of frost over the exterior of the container.

In Figs. 1 and 2 are disclosed a base 10 for 50 beverage cooling device, such base preferably

having a refrigerant liquifying unit therein such as is fully disclosed in my co-pending application, Serial No. 289,549. A base 11 of the beverage cooling section rests upon this main base 10 and supports a plurality 55 of outer side panels 12 enclosing insulation panels 13 such as cork board, a frame work indicated at 14, and an inner lining 15 of the beverage chamber or compartment 30. The inner sides of the outer panels and the 60 outer sides of the inner panels and the cork and cracks therebetween is thoroughly coated with a bituminous cement. A faucet 16 extends from the beverage chamber thru to the outer panel, preferably thru a reinforcing 65 piece of wood 17. Insulation 18, preferably of hard rubber, covers the upper edge of the walls of the chamber and supports an inner cover 19 thereon. The cover 19 has a collar 20 with another insulation collar 21, preferably also of rubber, for supporting the container 22. This container is preferably of the bottle type and the form disclosed is generally referred to as a demijohn.

In Fig. 1 a transparent glass 23 surrounds 75 a part of the bottle and has an insulating collar 24, preferably of hard rubber, inserted between it and the upper portion of the inverted bottle.

In Fig. 2 the invention is modified by having the transparent glass cover 33 enclose the inverted bottle 22. The transparent glass covers 23 and 33 rest upon the rubber insulation 18. In either modification the bottle 22 can be readily removed. In Fig. 1 it can be 80 withdrawn vertically upward and in Fig. 2 it can be likewise withdrawn vertically upward after the removal of the cover 33.

The liquid refrigerant supply line 25 extends thru one of the walls of the beverage 85 chamber to an expansion valve 26. This line preferably extends from a refrigerant liquifying unit in the base 10 referred to above. A conduit 27 extends upwardly from expansion valve 26 to a plurality of coils 28 about the 90 inverted bottle. The conduit may then descend into the beverage chamber where it may have a further plurality of coils 29. From these coils there may be a suction line return 95 for the refrigerant by means of the conduit 100

31 preferably returning to the refrigerant liquefying unit in the base 10.

5 A thermostat 32 may be located in the chamber 30 to control the refrigerant supply according to the temperature of the chamber.

10 Various modifications may be made in the apparatus. It is not essential that the coils 28 and 29 should be formed from a continuous conduit, altho it is preferred to do this. Furthermore, another type of system 15 may be used instead of the expansion system disclosed. Various modifications in the form and shape of the chamber and the container may be made.

20 15 It will thus be noted that the liquid refrigerant will first be sent around the container and will provide frost producing means for the exterior of this container. It will be necessary that a certain amount of moisture be contained in the space enclosed by the transparent covers 23 and 33 in order to produce this frost. Accordingly, the connection of these covers with the insulation 18 is not made so tight as to shut off this moisture. If desired, a certain amount of moisture may be 25 placed on the cover 19 in order that a production of frost may be insured on the outside of the bottle 22. It is not desired, however, to produce such a heavy frost that there is any danger of freezing the contents of the bottle. It is desired, however, to produce a sufficient amount to pre-cool the liquid in the bottle, and especially to call the customer's 30 attention to the fact that an efficient cooling 35 means has been installed in the beverage dispensing apparatus.

40 Accordingly there has been disclosed a beverage cooling and dispensing apparatus having a pre-cooling and frost producing means applied to the container discharging into the beverage compartment.

45 While the form of embodiment of the invention as herein disclosed, constitutes a preferred form, it is to be understood that other forms might be adopted, all coming within the scope of the claims which follow.

What is claimed is as follows:

50 1. A beverage cooling and dispensing apparatus comprising an insulated beverage chamber, a removable beverage container supported in an inverted position above said chamber and having its opening projecting into said chamber, mechanical cooling means about said container and mechanical cooling 55 means in said chamber.

60 2. A beverage cooling and dispensing apparatus comprising an insulated beverage chamber, a beverage container having an opening into said chamber, an expansion coil about said beverage container, an expansion coil in said chamber, and transparent means enclosing said first named expansion coil.

65 3. A beverage cooling and dispensing apparatus comprising an insulated beverage chamber, a removable demijohn having an

70 opening projecting into said chamber, cooling means about said demijohn, said demijohn being removable independently of said coating means, cooling means in said chamber, and transparent means enclosing said first mentioned cooling means.

75 4. A beverage cooling and dispensing apparatus comprising an insulated beverage chamber, a removable demijohn supported in an inverted position above said chamber and having its opening projecting into said chamber, cooling means about said demijohn, said demijohn being removable independently of said cooling means, cooling means in said chamber, and transparent means enclosing said first mentioned cooling means.

80 5. A beverage cooling and dispensing apparatus comprising an insulated beverage chamber, a cover for said chamber, a beverage container supported by said cover and having an opening projecting into said chamber thru said cover, a frost producing coil about said container and a cooling coil in said chamber.

85 90 6. A beverage cooling and dispensing apparatus comprising an insulated beverage chamber, a cover for said chamber, a beverage container supported by said cover and having an opening projecting into said chamber thru said cover, a frost producing coil about said container, a cooling coil in said chamber, and transparent means enclosing said frost producing coil.

95 100 105 7. A beverage cooling and dispensing apparatus comprising means for supporting a bottle in inverted position, means for dispensing liquid from said inverted bottle, and a heat absorbing refrigerant circulating device surrounding and in direct heat exchange relationship with at least a portion of said bottle while it is supported by said first named means and in heat exchange relationship with the surrounding air.

110 115 120 8. A beverage cooling and dispensing apparatus comprising means for supporting a bottle in inverted position, means for dispensing liquid from said inverted bottle, a heat absorbing refrigerant circulating device surrounding and in direct heat exchange relationship with at least a portion of said bottle while it is supported by said first named means and in heat exchange relationship with the surrounding air, and a transparent cover surrounding said device.

In testimony whereof I hereto affix my signature.

HARRY B. HULL.
